CLAIM

The ornamental design for a holder for a generator, as shown and described.

DESCRIPTION

FIG. 1 is a left side elevational view of the holder for a generator showing my new design;

FIG. 2 is a front elevational view thereof;

FIG. 3 is a side elevational view thereof;

FIG. 4 is a rear elevational view thereof;

FIG. 5 is a top plan view thereof; and

FIG. 6 is a fragmentary sectional view thereof taken along line 6—6 of FIG. 2.

FIG. 5

FIG. 6
